Patented July 6, 1976

240,419

SHELTER FOR RAPID TRANSIT AND BUS STATIONS

William R. Cooke, 49 Fitzgerald Road,
Marlboro, Mass. 01752

Filed Oct. 2, 1974, Ser. No. 511,483

Term of patent 14 years

Int. Cl. D25—03

U.S. Cl. D25—56

FIG. 1

FIG. 3

FIG. 2

FIG. 1 is a perspective view of a shelter for rapid transit and bus stations;

FIG. 2 is an elevational view of one side of the shelter, all of the sides of which are identical, and

FIG. 3 is a top view of the shelter.

I claim:

The ornamental design for a shelter for rapid transit and bus stations, as shown and described.
